UNITED STATES PATENT OFFICE.

HORATIO A. FOSTER, OF NEW YORK, N. Y.

ORDER-BOOK.

SPECIFICATION forming part of Letters Patent No. 443,189, dated December 23, 1890.

Application filed October 4, 1889. Serial No. 326,070. (No model.)

To all whom it may concern:

Be it known that I, HORATIO A. FOSTER, a citizen of the United States, and a resident of New York city, New York, have invented certain new and useful Improvements in Order-Books, of which the following is a specification.

My present invention relates to the construction of an order-book for use in manufacturing establishments where blanks are filled in with certain orders to install electric lighting in houses and towns and given to the men who are to carry out the order.

The invention is applicable to other books, also—as, for instance, to coupon-books published by the Patent Office and containing orders for copies of United State patents.

The object of the invention is to furnish a convenient means of registering when the order has been or has not been fulfilled, or when it has or has not been partially fulfilled.

The invention is described with especial reference to its application to books from which orders are taken by electric light and power men when they are instructed to fit up a house with wiring or to install a plant in any given place.

The device is described by reference to the accompanying drawings, in which—

Figure 1 is a view in partial perspective of such a book, with the cover partly broken away and with some of the orders omitted, showing the means of registering both as to partial fulfillment of order and complete fulfillment. Fig. 2 is a plan view of a complete leaf from the order-book, in which the order is blank and is all ready to be filled in, but which order has not yet been torn from the book.

In the figures, *a* is the book. *b* is a complete leaf or sheet of the book, and consists of the combination of a stub *c*, upon which a certain order may be registered. This order is repeated in the blank or order proper *d*. Between the order-blank *d* and the stub *c* are one or two (two shown in the figures) or even more indicating-slips *e* and *f*. In order that at certain times the slips *e* and *f* may be torn from the stub with convenience, the paper is perforated by the holes represented by the dots *g*, *h*, and *i*, respectively. These holes are arranged in straight lines,

and may be called, therefore, "perforated lines" *g*, *h*, and *i*.

When the order-blank is filled out in any convenient manner and given to the operator, it is first torn off from the sheet *b* at the line *i*. The words "Construction not finished," or words to that effect, are printed upon each strip *f* from the beginning to the end of the book. As long as this strip remains in the book attached to a particular stub it indicates that the construction of the plant requested by the order *d* has not been effected. When the operator reports, however, that the order has been fulfilled the slip *f* is torn from the stub. On the slip *e* are printed the words "Not started to burn," or words to that effect are printed on each slip *e* from the beginning to the end of the book. Just as soon as the operator reports that the order has been also completed in regard to the fact that the electric lamps have been turned on and the system is in operation, then, and not until then, is the slip *e* torn from the stub. The strips *e* are therefore indicating-strips, in that they indicate by their presence that an order has not been fulfilled in part or in whole, and by their absence that the order has to a predetermined extent been positively carried out.

It is evident from the nature of the invention that the sheet *b* may represent any kind of an order—such as that which has been intimated or such as a check or any thing in the nature of a written request—which is given by the owner of the book to another individual or party. The stub is merely for a memorandum of what has been written on the order. It is evident that the owner of the book may have printed upon the intermediate strips any suitable words calling attention to the fact that certain parts or all of the order has not been fulfilled.

The particular words on the sheets shown in Fig. 1 indicate that parts of the order may be first printed in the book; but the particular words therein made do not have anything to do with my invention.

The strip *c* may be termed a "permanent stub," as the same is for the purpose of forming a permanent memorandum, while for somewhat similar and apparent reasons the slips *e* and *f* may be termed "temporary stubs." The construction is different in the two cases, be-

cause they are similar only in having a stub. The similarity with the disclaimer in Small's patent is found only in the stub and the coupon or order-slip. The difference consists in 5 the fact that applicant has a slip or strip *e*, which is neither a stamp portion nor a coupon, nor an address portion nor a receipt portion. It is a temporary stub or temporary memorandum, or temporary indicating-slip, or, in 10 general, means for indicating that the order has not been fulfilled. As to what the slip indicates, an example is pointed out in the specification (applicant's) on page 3, lines 15 to 20, inclusive. The constructive difference 15 is incorporated in the amended claims below.

I claim as my invention—

1. In an order-book, a sheet consisting of the combination of a stub *c*, attached to the book, and an order-blank *d*, attached to the said 20 stub, indicating-slips containing the words "Construction not finished," or words to a similar effect, and attached to both the stub and the order-blank, the said sheet being provided with perforated lines between the said 25 words or slips and both the said stub and the said order-blank.
2. In a blank order-book, the combination

of three detachable slips forming a permanent stub attached directly to the book, a temporary stub, for the purpose described, attached directly to the said first stub, and an order or coupon attached directly to the temporary stub. 30

3. The hereinbefore-described method of indicating in a book having coupons and 35 stubs the fulfillment or partial fulfillment of an order, such as an order to install and start an electric-light plant, consisting in writing the order upon a coupon and one of the stubs of a blank-book at the time the order is given 40 and tearing off or similarly removing another stub, said last stub being appropriately termed a "temporary stub" at the time when the fulfillment or partial fulfillment of the order occurs or is reported. 45

In testimony that I claim the foregoing as my invention I have signed my name, in presence of two witnesses, this 1st day of October, 1889.

HORATIO A. FOSTER.
